US00D946418S

(12) **United States Design Patent** (10) Patent No.: **US D946,418 S**
 Gonzalez Manzano et al. (45) Date of Patent: **** Mar. 22, 2022**

(54) CARRIER	2,965,410 A *	12/1960	Hughes	B65D 71/42
				294/87.2
(71) Applicant: Graphic Packaging International, LLC , Atlanta, GA (US)	3,001,647 A	9/1961	Liss	
	3,046,711 A	7/1962	Harrison	
	3,061,141 A	10/1962	Cote	
	3,099,475 A	7/1963	Manizza	
(72) Inventors: Ana Maria Gonzalez Manzano , Igualada (ES); Steve M. Gould , Bristol (GB)	3,118,537 A	1/1964	Copping	
	3,137,109 A	6/1964	Rapata	
	3,146,885 A *	9/1964	Hughes	B65D 71/20
				206/429
(73) Assignee: Graphic Packaging International, LLC , Atlanta, GA (US)	3,200,944 A	8/1965	Rapata	
	3,245,711 A *	4/1966	Dantoin	B65D 71/44
				294/87.2
(**) Term: 15 Years	3,281,180 A	10/1966	Sperry	
(21) Appl. No.: 29/739,929	3,302,784 A	2/1967	Copping	
(22) Filed: Jun. 30, 2020	3,387,879 A	6/1968	Wood	
(51) LOC (13) Cl. 09-03	3,432,202 A	3/1969	Ebelhardt

CLAIM

The ornamental design for a carrier, as shown and described.

DESCRIPTION

The disclosures of each of U.S. Provisional Patent Application No. 62/779,689, filed on Dec. 14, 2018, U.S. Provisional Patent Application No. 62/783,752, filed on Dec. 21, 2018, U.S. Provisional Patent Application No. 62/796,830, filed on Jan. 25, 2019, U.S. Provisional Patent Application No. 62/797,585, filed on Jan. 28, 2019, U.S. Provisional Patent Application No. 62/810,015, filed on Feb. 25, 2019, U.S. Provisional Patent Application No. 62/814,412, filed on Mar. 6, 2019, U.S. Provisional Patent Application No. 62/817,120, filed on Mar. 12, 2019, U.S. Provisional Patent Application No. 62/841,449, filed on May 1, 2019, U.S. patent application Ser. No. 16/426,050, filed on May 30, 2019, U.S. Patent Application Ser. No. 16/426,057, filed on May 30, 2019, U.S. patent application Ser. No. 16/426,060, filed on May 30, 2019, U.S. patent application Ser. No. 16/426,063, filed on May 30, 2019, U.S. patent application Ser. No. 16/426,066, filed on May 30, 2019, U.S. Design patent application Ser. No. 29/692,992, filed on May 30, 2019, U.S. Design patent application Ser. No. 29/692,993, filed on May 30, 2019, U.S. Design patent application Ser. No. 29/692,994, filed on May 30, 2019, U.S. Design patent application Ser. No. 29/692,996, filed on May 30, 2019, U.S. Design patent application Ser. No. 29/692,997, filed on May 30, 2019, U.S. patent application Ser. No. 16/598,282, filed on Oct. 10, 2019, U.S. Design patent application Ser. No. 29/709,918, filed on Oct. 18, 2019, U.S. Provisional Patent Application No. 62/952,839, filed on Dec. 23, 2019, U.S. Provisional Patent Application No. 62/956,882, filed on Jan. 3, 2020, U.S. Provisional Patent Application No. 62/985,997, filed on Mar. 6, 2020, U.S. Patent Application No. 16/829,346, filed on Mar. 25, 2020, U.S. Provisional Patent Application No. 63/015,898, filed on Apr. 27, 2020, U.S. Provisional Patent Application No. 63/022,757, filed on May 11, 2020, and U.S. Provisional Patent Application No. 63/023,442, filed on May 12, 2020, U.S. Design patent application Ser. No. 29/735,178, filed on May 19, 2020, and U.S. Provisional Patent Application No. 63/031,615, filed on May 29, 2020, are hereby incorporated by reference for all purposes as if presented herein in their entirety.

FIG. 1 is a perspective view of a carrier showing our new design.

FIG. 2 is a front elevation view of the carrier of FIG. 1, the rear elevation view is a mirror image.

FIG. 3 is a left elevation view of the carrier of FIG. 1, the right elevation view is a mirror image.
